H. D. ROBINSON.

CABLE SQUEEZER.

APPLICATION FILED JAN. 7, 1909.

926,609.

Patented June 29, 1909.

UNITED STATES PATENT OFFICE.

HOLTON D. ROBINSON, OF NEW YORK, N. Y.

CABLE-SQUEEZER.

No. 926,609.

Specification of Letters Patent. Patented June 29, 1909.

Application filed January 7, 1909. Serial No. 471,098.

To all whom it may concern:

Be it known that I, HOLTON D. ROBINSON, a citizen of the United States, and a resident of the city of New York, borough of Manhattan, in the county and State of New York, have invented a new and Improved Cable-Squeezer, of which the following is a full, clear, and exact description.

In the forming of cables for suspension bridges and the like, in which each cable is formed of a plurality of separate strands or wires bound together, considerable difficulty is often encountered in squeezing the strands together, to form a perfectly cylindrical cable, in bringing sufficient pressure to draw all strands into firm engagement with each other, and in holding the strands in position while the permanent clamps, wrappings or other inclosing means, are being placed in position.

The object of my invention is to provide a device which may be easily and quickly applied to the mass of strands going to make up the cable, which will force them together into a perfectly cylindrical mass, and which may be very readily loosened and moved after the permanent securing means has been applied adjacent the point last squeezed into shape.

Reference is to be had to the accompanying drawings forming a part of this specification, in which similar characters of reference indicate corresponding parts in all the figures, and in which—

Figure 1 is an end view of a cable squeezer constructed in accordance with my invention; Fig. 2 is a top plan view of the device shown in Fig. 1, the device for drawing the members together being broken away; Fig. 3 is a sectional view on the line 3—3 in Fig. 1; and Fig. 4 is a side elevation showing a modified form of pressure-applying means, parts being broken away and in section.

My improved cable squeezer is formed of two separate semi-circular members 10 and 11, hinged together at one end and having means for forcing the opposite ends together. Each member has an inner band portion 12 presenting a smooth surface for direct contact with the strands or wires going to make up the cable, and outside of this inner band portion is an outer or reinforcing portion 13 of any suitable form in cross section. The two members are secured together by a pivot pin 14, one of the members having two leaves or projections 15, 15, for receiving the

pivot pin, and the other member having a center leaf or projection 16 disposed intermediate the two leaves or projections 15, 15. As these hinged leaves or projections overlap and their inner surfaces lie in the arc of the same circle with the inner surfaces of the two members, it is evident that there is no transverse line or groove extending entirely across the device at the hinge and into which any wire or strand could be forced during the squeezing operation. The opposite end of one member is provided with two fingers or projections 17, 17, extending on opposite sides of a central finger or projection 18 carried by the other member. These overlapping fingers or projections 17 and 18 lie diametrically opposite to the hinge pin 14 and when drawn past each other to the proper extent, the inner surfaces of the two members and their overlapping projections at both the upper and the lower portions, form a perfect cylindrical bore or passage.

For drawing the two members together, each is provided with two upwardly-extending parallel lugs 19, 19, and each pair of lugs supports a transverse pivot pin 20. These lugs extend upwardly from their respective members to such an extent that a line connecting the pivot pins 20 will lie entirely outside of the cylindrical bore or passage and beyond the overlapping fingers or projections 17 and 18. Connecting these two pivot pins is a suitable means for drawing them toward each other and causing the two members to come to the position indicated in Fig. 1. In the specific form illustrated in Fig. 1, this pressure-applying means includes two sections 21 and 22, each pivoted to its corresponding pivot pin 20, and one of said sections constituting or having a cylinder 23, and the other constituting or having a piston 24 mounted within said cylinder. The section 21 having the cylinder 23 is provided with a cylinder head 25 and a gland 26 for forming a tight joint about the piston rod portion of the section 22. Adjacent the cylinder head 25 is an inlet 27, to which a suitable delivery pipe may be connected, and at the opposite end of the cylinder is a small air-escape passage 28, through which air may enter or escape from the cylinder during the operation of the device. In use, one of the sections is detached from its pivot pin 20, the two members 10 and 11 are opened up on the hinge pin 14 and are brought together again about the large num-

ber of wires or strands going to make up the cable. The detached section is again secured to its pivot pin 20 and liquid is forced into the cylinder 23 under high pressure until 5 the fingers or projections 17 and 18 have been overlapped, so that the inner surfaces of the two members lie in the arc of the same circle. The permanent clamping means is then applied to the cable to retain the strands in 10 position, the liquid is permitted to escape through the opening 27, and the cable squeezer is moved along the cable a short distance to a convenient point. It is unnecessary to separate either of the sections 15 from its member after the device has once been placed around the strands.

For use with small cables or in center cores of large cables, a turnbuckle may be used in place of the hydraulic means illustrated in 20 Fig. 1. In Fig. 4 I have illustrated such a turnbuckle, which includes two flat sections 21^a and 22^a, pivoted to the pins 20 and having right-hand and left-hand threads. In- 25 closing the two threaded sections is a sleeve 29, which when rotated draws the two sections together with the desired pressure.

In either form of the device, it will be noted that the pressure-applying means is at one side of the cable, and that the two mem- 30 bers move relatively to each other about a pivot pin diametrically opposite to the pres-

sure-applying means. Thus, the two mem- bers in themselves constitute levers and per- mit of a greater pressure being applied to the strands of the cable than is exerted at the pivot pins 20.

Having thus described my invention, I claim as new and desire to secure by Letters Patent:

A cable squeezer, comprising two semi- circular members having overlapping leaves or projections at one end, a hinge pin extending through said leaves or projections, overlapping fingers diametrically opposed to said hinge pin, outwardly-extending lugs carried by said members adjacent said fingers, and means for moving said members toward each other and about said hinge pin, said means including two sections, having their outer ends pivotally connected to the lugs of the members, said sections being in alinement with each other between the two connec- tions, and said sections being longitudinally movable relatively to each other.

In testimony whereof I have signed my name to this specification in the presence of two subscribing witnesses.

HOLTON D. ROBINSON.
